UNITED STATES PATENT OFFICE

RICHARD C. FAGAN, OF MIDDLETOWN, CONNECTICUT, ASSIGNOR TO THE RUSSELL MANUFACTURING COMPANY, OF MIDDLETOWN, CONNECTICUT, A CORPORATION OF CONNECTICUT

DESIGN FOR A WOVEN ELASTIC WEBBING

Application filed January 29, 1932. Serial No. 42,666. Term of patent 7 years.

To all whom it may concern:

Be it known that I, RICHARD C. FAGAN, a citizen of the United States, and a resident of Middletown, in the county of Middlesex and State of Connecticut, have invented a new, original, and ornamental Design for Woven Elastic Webbing, of which the following is a specification, reference being had to the accompanying drawing, forming part thereof, in which—

The figure is a face view of a piece of web-

bing partially stretched and embodying my invention.

The characteristic features of the design comprise the three stripe effect with lateral projections similar to rake teeth projecting from the first stripe of each group.

I claim:

The ornamental design for woven elastic webbing as shown and described.

RICHARD C. FAGAN.
